W. H. WAKEFIELD

FILLING STOP MOTION FOR LOOMS

Filed Dec. 14, 1925

UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

FILLING STOP MOTION FOR LOOMS.

Application filed December 14, 1925. Serial No. 75,183.

This invention relates to filling stop motions for looms and it is the general object of the invention to simplify the center stop motion of the well known Knowles loom to the 5 end that the same may be operative with fewer parts without sacrificing reliability of operation.

When the filling breaks or becomes exhausted during the weaving process a short 10 end is likely to remain in the shed which when beaten up leaves a thin place in the fabric. If the broken end is long enough to support the filling fork and the shuttles change on the next pick, weaving may continue, but ultimately the shuttle with defective filling will again become active and will stop the loom through the action of the 15 stop motion. The weaver must then remove all the picks laid after the short pick was beaten up and must also remove the defective 20 pick. This leaves the shed of the loom in the position it was on the pick before the passage 25 of the shuttle which laid the faulty pick but of course the pick which was laid in that shed when the latter was originally open has already been beaten in place and for that reason is not behind and under the filling fork. Therefore as the lay moves forwardly 30 the fork of the stop motion will be unsupported and would stop the loom unless provision were made to prevent stopping and 35 permit continued running.

As heretofore constructed stop motions of the type referred to have been provided with 40 a sheet steel shield which when the loom stops is always raised to such a position as will hold the dagger of the stop motion out of contact with the actuating lever which is rocked by the dagger to effect stopping of the 45 loom. Because of this shield it is possible to start up the loom when no filling is in the shed, the first forward movement of the lay after pick-out resulting in moving the shield down out of shielding position so that on the next and subsequent forward movements the actuating lever will be exposed to the action of the dagger should filling be 50 absent.

It is an important object of my invention 55 to dispense with the shield and resetting lever therefor but retain the function of these parts, permitting the loom to run for the first pick even though no filling be in the

shed. The mechanism comprises generally an actuating lever which is moved to initial 55 position when the loom stops and is moved to normal running position on the first pick of the loom. Provision is made to hold the actuating lever yieldingly in normal position by connections from the shipper mechanism 60 when the loom is running and to release the actuating lever so it can return to initial position by the same connections when the loom is stopped. In order to prevent the dagger from constantly striking the actuating lever when the latter is in normal position said lever has the end thereof below the path usually traversed by the dagger when 65 weft is present.

With these and other objects in view which 70 will appear as the description proceeds, my invention resides in the combination and arrangement of parts hereinafter described and set forth in the claims.

In the accompanying drawings wherein I 75 have shown a convenient embodiment of my invention,

Fig. 1 is a transverse section through a portion of a loom showing my invention applied thereto with the stop motion in the 80 position it assumes when the loom is being started up immediately after a pick-out with the lay advancing, the actuating lever being in its initial position,

Fig. 2 is a view similar to Fig. 1 but showing the actuating lever being moved to its 85 second or normal position,

Fig. 3 is a view similar to Fig. 1 but showing the parts on a subsequent pick when filling is absent and the actuating lever is 90 being moved from normal to knocking off position,

Fig. 4 is a top plan view of the parts in the position shown in Fig. 2 looking in the direction of arrow 4 of said figure, 95

Fig. 5 is a rear detail elevation looking in the direction of arrow 5, Fig. 1,

Fig. 6 is a vertical detail section on line 6-6 of Fig. 2, and

Fig. 7 is a diagrammatic view on an enlarged scale showing the paths followed by the dagger on the lay under various conditions.

Referring to the drawings it will be seen that I have provided a loom side 10 having 100 a breast beam 11 to the rear face of which

is secured a bracket 12 having a rearwardly extending arm 13 and a depending arm 14. Said arm 13 has secured thereto a cam plate 15 having a forwardly and downwardly extending cam face 16 to guide a dagger 17. Said dagger is secured in the forward end of a lever 18 pivoted as at 19 to a bracket 20 secured to the under side of the lay 21. A link 22 pivotally connected to the lever 18 extends upwardly and is attached to an arm 23 formed on a stub shaft 24 which extends through a small bracket 25 carried on the forward face of the lay 21. A small block 26 moves with the arm 23 and shaft 24 and has secured thereto filling fork tines 27 which are positioned to enter a slot S in the lay 21.

A shipper shaft 28 journaled in the loom frame has secured thereto a shipper handle 29 and the hub 30 of a knock-off lever 31, said lever 31 moving angularly with shaft 28. Depression of lever 31 from the position shown in Fig. 1 will move the shipper handle 29 to the right to stop the loom.

Extending laterally from and secured to arm 14 is a stud 32 on which is loosely pivoted the hub 33 of an actuating lever 34. Said lever 34 has a laterally extending lug 35 which lies over lever 31 so that when the actuating lever is moved to the left from the position shown in Fig. 1 knock-off lever 31 will be depressed to rock shipper shaft 28. A collar 36 is secured to the stud 32 and receives one end of a coiled torsion spring 37 the other end of which is received by the hub 33 to hold the lever 34 yieldingly to the right in the position shown in Fig. 1. The matter thus far described is of well known construction and forms no part of my present invention.

In carrying out my present improvements I provide means for moving the actuating lever from an initial to a normal position on the first pick after a pick-out and provide also for retaining the lever in its normal position by means of a latch which moves with the shipper shaft. Referring particularly to Figs. 1, 2, and 3 it will be seen that I have provided the actuating lever 34 with a notch 50 which is always in advance of the cam face 16 and have further provided said actuating lever with a second notch 51 which when the lever is in initial position shown in Fig. 1 will lie behind the cam face 16 and be held against a lug 52 rigid with the arm 13 by spring 37.

As shown in Figs. 4 and 5 I provide the lever 34 with a laterally extending lug 53 having an extended lower face 54. A flat spring or latch 55 has a slot 56 in the forward end thereof through which passes a screw or bolt 57 threaded into a flattened portion of hub 30 to hold said latch against the hub and cause these parts to move together. The rear end of spring or latch 55 is formed with a

tooth or hook 58 proportioned to engage the rear end of lug 53 and normally lying over the axis of stud 32 so that any pressure exerted thereby against lever 34 will be radial with respect to torsion spring 37. A cam 60 extends upwardly from arm 13 for a purpose to be described. The lever 31 is provided with a set screw 59 which normally lies over the leaf spring or latch 55 to move said latch down positively away from lug 53 when the shipper handle moves to stop the loom.

In operation, after the loom has been stopped, the parts will be in the initial position shown in Fig. 1 with the rear notch 51 of the actuating lever held against lug 52 by spring 37.

After the weaver has finished picking out the shipper handle will be pulled forward to start the loom to the position shown in Fig. 1 and the lay 21 will move forwardly.

As it does so dagger 17 will move down the inclined face 16 and as filling is absent, the tines 27 will move into slot S, thus permitting the dagger to descend until it engages actuating lever 34.

As the lay 21 continues to advance the dagger will enter notch 50 and move the actuating lever from the position shown in Fig. 1 to the position shown in Fig. 2. The latch 55 was raised when the shipper handle was pulled on to start the loom and as lever 34 is moved to the position shown in Fig. 2 the hook 58 will rise behind lug 53 to hold the actuating lever in the normal position shown in Fig.

2. Continued forward movement of the lay will cause the dagger to rise on the rear face of cam 60 to be lifted out of notch 50, and the dagger will move forwardly to the end of its motion without further action on the stop motion. Notch 51 is now in front of cam face 16 and above arm 13 but below the path usually traversed by the dagger and indicated by the dotted line U in Fig. 7. On all succeeding advancing movements of the lay, when weft is present, the dagger 17 will be held in raised position following the path indicated at U and will pass over the notches 50 and 51 without engaging the same.

When filling is absent, however, the dagger 17 will be lowered to engage the rear notch 51 to give the actuating lever a second forward movement from the normal position shown in Fig. 2 to the knock-off position shown in Fig. 3. This last motion of the actuating lever will cause lug 35 to depress lever 31 and the shipper shaft 28 will be given a right hand movement to rock the shipper shaft 28 and move handle 29 to stopping position. It will be seen that as soon as the shipper shaft moves to the right to the position indicated in Fig. 3 the resilient latch 55 will be moved down away from lug 53 so that as soon as dagger 17 leaves notch 51 spring 37 will be free to return the actuating lever to the initial position shown in Fig. 1.

In this way lever 34 is returned to initial position every time the shipper shaft moves to stopping position.

It will be seen that the actuating lever 34 will be moved to initial position every time the loom stops, but obviously the loom will be started with the lever in this position when weft is present, as after stopping due to the protector mechanism or warp stop motion. Under these conditions it is desirable to move the lever 34 to normal position and to accomplish this result the notch 50 is high enough to extend above the path normally traversed by the dagger when filling is present and lever 34 is in the initial position. On the first pick with filling present therefore, the dagger will engage notch 50 and move with the same about stud 32 along a path similar to the dot and dash line M in Fig. 7 to a point below the dotted line U of Fig. 7 before being disengaged by cam 60. As in the previous instance, therefore, the notch 50 will be below the normal path of the dagger.

From the foregoing it will be seen that I have provided a filling stop motion with an actuating lever movable from initial to normal position on the first pick after a pick-out and that the actuating lever is movable from normal to knock-off position upon a subsequent absence of filling. It will further be seen that the latch for holding the lever in normal position moves to releasing position when the shipper handle is thrown off, thus permitting the actuating lever to be restored to initial position. Furthermore, the tooth of the latch moves in a direction substantially radial from the axis of stud 32 so as to have little or no effect on the action of torsion spring 37. Also, that portion of the actuating lever which is engaged by the dagger when said lever moves from initial to normal position is held by latch 55 in a position below the normal path of the dagger so as to be out of the path of said dagger.

Having thus described my invention it will be apparent that changes and modifications may be made therein by those skilled in the art without departing from the spirit and scope of the invention, and I do not wish to be limited to the details herein disclosed but

What I claim is:

1. In a filling stop motion for looms, a shipper shaft, a movable actuating member having a pair of operating faces, a dagger movable back and forth in the loom and controlled as to its position by weft, means to shield one of said faces from the dagger when the actuating member is in initial position, means moving with the shipper shaft to hold the actuating member locked when the other face of the actuating member is in operative position with respect to the dag-

ger, and connections to effect angular movement of the shipper shaft to stop the loom when the dagger engages said other operative face of the actuating member, the locking means moving with the shipper shaft out of locking position with respect to the actuating member when the shipper shaft moves to stop the loom.

2. In a filling stop motion for looms, a lay, a shipper shaft, a bracket held in fixed position, an actuating lever pivoted to the bracket, a dagger on the lay and controlled as to position by the weft, a cam face on which the dagger moves as the lay advances, an operating face on the actuating lever held out of the path of the dagger when said actuating lever is in its initial position, a second operating face formed on the actuating lever in advance of the first named face and positioned for engagement with the dagger when weft is present, a lock moving with the shipper shaft to hold the actuating lever in normal position with the first named operating face in advance of the cam face after engagement of the dagger and second named operating face, the lock moving angularly with the shipper shaft away from the actuating lever to release the same when the shipper shaft is moved to stopping position.

3. In a filling stop motion for looms, a lay, a member movable back and forth with the lay and controlled as to position by the weft and normally traversing a prescribed path when weft is present, shipper mechanism, an actuator for the shipper mechanism having two portions to be engaged by the member, one of said portions extending above the prescribed path of the member and movable by the latter to a position below the prescribed path, and the other of said portions lying below the prescribed path to be engaged by the member whereby said member will move the actuator when weft is absent.

4. In a filling stop motion for looms, a lay, a member carried by the lay and normally traversing a prescribed path when weft is present and moving through a second path when weft is absent, shipper mechanism, an actuator for the shipper mechanism having two portions one of which lies above the normal prescribed path to be engaged by the member when weft is present and move to a position below the normal prescribed path, means controlled by the shipper mechanism to hold the actuator with the said portion below the prescribed path and the second portion of the actuator above the second named path to be engaged by the member when weft is absent to move the actuator to control the shipper mechanism.

5. In a filling stop motion for looms, a lay, a member movable on and moving therewith and normally traversing a prescribed

path when weft is present and moving through a second path when weft is absent, shipper mechanism, an actuator for the shipper mechanism to assume three positions in one of which a portion of the actuator extends above the normally traversed path of the member when weft is present to be engaged by the member and moved to a second position, said actuator when in the second position having another portion below the normally traversed path of the member but above the second named path to be engaged by the member when weft is absent, and moved to the third position into engagement with the shipper mechanism to stop the loom.

6. In a filling stop motion for looms, a lay, a member carried thereby and con-

trolled as to position by the weft and normally traversing a prescribed path when weft is present, an actuator extending into the prescribed path, shipper mechanism to be controlled by the actuator, said member engaging the actuator and moving therewith to a point below the prescribed path, means controlled by the shipper mechanism to hold the actuator in a position below the prescribed path when moved to such position by the member, and a cam to be engaged by the member as the latter continues to move to restore said member to the prescribed path.

In testimony whereof I have hereunto affixed my signature.

WALTER H. WAKEFIELD.
